UNITED STATES PATENT OFFICE.

JACOB N. MCINTIRE, OF NEW YORK, N. Y., ASSIGNOR TO THE BRUNSWICK-BALKE-COLLENDER COMPANY, OF CHICAGO, ILLINOIS.

BOWLING-ALLEY.

SPECIFICATION forming part of Letters Patent No. 642,801, dated February 6, 1900.

Application filed September 29, 1899. Serial No. 732,010. (No model.)

To all whom it may concern:

Be it known that I, JACOB N. MCINTIRE, a citizen of the United States, residing at New York city, Manhattan borough, in the county and State of New York, have invented certain new and useful Improvements in Bowling-Alleys, of which the following is a specification.

My invention relates wholly to that portion 10 of a bowling-alley which is commonly denominated the "ball-return way" and to that type or kind of ball-return way in which the balls are delivered onto the rearmost end of the ball terminal or rack, a sample of which type 15 of return-way is shown and described in United States Letters Patent No. 630,728, granted August 8, 1899.

My invention has for its objects to improve this kind of return-way in two particulars, 20 viz: first, to render it capable of returning with more certainty or ease (under all conditions under which a return-way may have to be used) onto the ball-terminal the smallest-sized ball of the series of larger balls, (which 25 is usually about six inches in diameter,) and, second, to overcome or avoid all possibility of such smallest ball jumping the track or bouncing off of the rear end portion of the terminal after having been delivered there- 30 onto, especially in cases in which said terminal may be composed (as it frequently is) of two parallel substantially horizontal ways, of either wood or metal.

To these ends and objects my invention 35 may be said to consist, primarily, in a novel form of the rearward-curved portion of the ball-track of the said type of return-way, this portion of the ball-track being curved in scroll form or substantially spirally in lieu 40 of running in a substantially circular curve, as heretofore; and, secondarily, in having the rear end portions of the wooden or metallic ways or bars of the ball-terminal slightly spread apart, preferably in curved lines, all 45 as will be hereinafter fully explained and as will be most particularly pointed out in the claims of this specification.

To enable those skilled in the art to make and use ball-return ways according to my in-

vention, either as to one or both features of 50 the latter and either (as to either part) in the precise form in which I have shown said invention carried out or under some modification thereof, I will now proceed to more fully describe my improved construction of ball- 55 return way, referring by letters and numerals to the accompanying drawings, which make part of this specification, and in which I have shown both features of said construction in the forms in which I have so far successfully 60 practiced my invention.

In the several figures the same part will be found always designated by the same letter or numeral of reference.

Figure 1 is a partial side elevation of one 65 of my improved ball-return ways shown with a portion of the long horizontal part of the ball-track removed or broken out and the end portions of the return-way moved toward each other or shown nearer together than they 70 are placed in practice for the purpose of getting such a view on a sheet of permissible size and at the same time have the scale sufficiently large to clearly exhibit the novel construction to be illustrated. Fig. 2 is a par- 75 tial top view, enlarged scale, of what is seen in elevation at Fig. 1, showing only the players' end portion comprising the ball-terminal, &c., and in this view the forwardly-projecting overhanging end portions of the curved ball- 80 tracks are, it will be seen, broken off in order that by this view may be better seen just how the rear end portions of the two bars or ways of the terminal are spread apart or made slightly divergent (preferably in curved 85 lines) as they extend back to the proper locality to catch the smallest-sized ball (usually about six inches in diameter) delivered onto said terminal. Fig. 3 is a detail vertical sec- 90 tion at the line $\alpha\alpha$ of Fig. 1 looking in the direction there indicated by arrow, but drawn on the same scale as that of Fig. 2, and sim- 95 plly showing especially the arrangement of the several sets of ballways constituting, respectively, the ball-returning track and the two terminals or ball-racks on which the home- sent balls rest for use by the players.

I have indicated by a heavy horizontal line,

so marked, the "floor" or level of the alley bed or beds of the alley or pair of alleys in connection with which the return-way shown is supposed to be used.

5 As usual, the ball-track starts, as at *a*, at a suitable elevation at the pit end of the alley to permit the placement thereon (or in a cage such as usually combined with this part *a*) of the balls to be sent back to the players' end 10 of the alley, from which point the track suddenly descends obliquely, as at *b*, and thence merges into the horizontal portion *c*, so that a ball put on at *a* will roll down the incline, as illustrated by circle 1, and travel thence 15 toward the players' end of the alley, as illustrated by circle 2, all about as usual in the type of return-way shown as heretofore made.

At the players' end is located the terminal (or main ball-rack) *g*, which is shown as composed of two cylindrical tubes of metal supported in about the usual manner (at a suitable elevation) by three metallic frames *m*, *o*, and *p*, the foremost one of which, *m*, is made or provided with a stop device *n*. These 25 frames *m o p* also support the tubular ways *i*, which constitute the usual rack for the series of smaller balls, which, as usual, are rolled or sent home in one of the ball-gutters of the alley and are placed by hand by an attendant 30 in the said rack formed of tubes *i*.

The ball-track (or set of ways) on which the balls roll home instead of being circularly curved upwardly and thence forwardly over the rear ends of the terminal bars or ways *g* 35 is, as plainly shown at *d e f* of Fig. 1, turned in an approximately spiral or volute-like curve, the effect of which is that a ball rolling from the lowermost horizontal portion *c* onto the curved part *d* of the ways, as illustrated at Fig. 1 by circle 3, will not meet with so abrupt an obstacle to its onward course, and hence will more easily or at a greater speed travel by its impetus up the part *e* of the track and thence along to the point (or approximately to the point) *f*, and thus more 45 certainly reach a point in its course of travel on the ways *d e f* from which it will descend onto the rear portion of the terminal *g*, along on which it will roll, as illustrated by circle 50 4 and the arrow, until its further progress is stopped either by contact with the stop *n* or with some ball previously returned onto the ways *g*. This scroll-like or sort of spiral form of the rearward-curved portion of the ball-track by which the balls are caused to 55 ascend to a level slightly above that of the terminal ways *g* and be delivered properly onto said terminal I have found by experiment and practice to constitute, practically, 60 a great improvement on the circular form, and in carrying into effect this feature of my invention it is not necessary, of course, to follow exactly the species of scroll or the exact curvature I have shown, the substantial effects of this novel feature being at-

tainable under mere modifications of or immaterial variations in this scroll-curved rear end portion of the ball-track. It is essential only that the curved portion *d e f* be such that the curve is comparatively flat as 70 the line leaves the horizontal part of the track and gradually increases in sharpness (or the suddenness of its curvature) as it approaches the part *f*, at about which the rolling ball descends nearly vertically onto the 75 rear end of the terminal ways *g*. These rear ends of the terminal in lieu of being merely curved upwardly, as seen at *h*, Fig. 1, as heretofore, (for the purpose of inciting the ball delivered thereonto to roll forwardly thereon, 80 as indicated by arrow at circle 4,) are also spread apart or diverge rearwardly, as shown at Fig. 2, so that in the event of the smallest-sized ball (which drops the greatest distance in descending from contact above with the 85 ball-track at the vicinity of *f* into contact with ways *g*) not striking simultaneously on the two ways *g* instead of tending to jump the track or actually bounding sidewise off of the terminal will settle down in between the 90 ways *g*, where they are more widely separated, and coming to a proper bearing on both ways will then roll forwardly thereon.

At Fig. 2 the dotted circle represents how a six-inch ball delivered onto the rear end of 95 terminal *g* will be delivered initially onto that part where the two ways are slightly divergent, and hence will be caught and retained by the said ways with more certainty than with these ways being the same distance 100 apart at every point, as heretofore in the construction of that type of return-way to which the just-above-described improvement relates.

Of course the exact degree of spread and 105 the extent of the divergence lengthwise of the ways must be determined by the judgment of the skilled alley-builder according to the surrounding circumstances and conditions, the elevation to which the balls are "lifted" 110 (so to speak) and the speed with which and the manner in which they may be discharged at the locality *f* of the particular return-way determining, in a measure, the proper precise forms of the laterally spread or divergent end 115 portions of the ways *g*.

Having now so fully described my improvements that any skilled alley-builder can construct a return-way embodying either one or both of the (separable) parts of my invention 120 in either the form shown as to either or under some mere modification of my invention, what I claim as new, and desire to secure by Letters Patent, is—

1. In a ball-return way of the type referred 125 to, a ball-track, the rearmost, upwardly-curved, portion of which is formed to present a scroll-like curve; that is, a curve, the sharpness of which increases, as it extends rearwardly upwardly and forwardly; all substan- 130

tially as and for the purpose hereinbefore set forth.

2. In a ball-return way of the type referred to, the combination, with the rear, curved, 5 end portion of the track on which the balls roll homewardly and from which they pass onto the terminal, or ball-rack, of a terminal, the rear ends of the ways of which are diver-

gent, or flared apart; all substantially as and for the purpose hereinbefore set forth. 10

In witness whereof I have hereunto set my hand this 22d day of September, 1899.

J. N. MCINTIRE.

In presence of—

R. W. DRUMMOND,
O. B. ACKERLY.
